Attorney.

UNITED STATES PATENT OFFICE.

FELIX H. PETITMAIRE, OF NEW YORK, N. Y.

COMBINED FOOT REST AND HEATER.

1,246,153.

Specification of Letters Patent. Patented Nov. 13, 1917.

Application filed October 23, 1916. Serial No. 127,224.

To all whom it may concern:

Be it known that I, FELIX H. PETITMAIRE, a citizen of the Republic of France, now residing at New York city, in the county of 5 New York and State of New York, have invented certain new and useful Improvements in Combined Foot Rests and Heaters; and I do hereby declare the following to be a full, clear, and exact description of the 10 invention, such as will enable others skilled in the art to which it appertains to make and use the same.

This invention relates to foot rests and foot warmers especially adapted for automobiles and has for its object to provide a 15 device of this character which will be simple in construction and more efficient in action than those heretofore proposed.

With these and other objects in view the 20 invention consists in the novel details of construction and combinations of parts more fully hereinafter described and particularly pointed out in the claims.

Referring to the accompanying drawings 25 forming a part of this specification in which like numerals designate like parts in all the views:—

Figure 1 is a longitudinal sectional view of an apparatus made in accordance with 30 this invention;

Fig. 2 is a view taken on the line 2—2 of Fig. 1, looking in the direction of the arrows; and

Fig. 3 is a view of the parts shown in 35 Fig. 1, but illustrating the same located flush with the floor of an automobile.

1 indicates the floor of an automobile or other floor to which it is desired to apply this invention, 2 an intake pipe supplying 40 hot gases to the heating member 3 of the foot warmer and 4 a pipe leading off the said gases from the heating member 5, of said foot warmer, all as will be clear from Fig. 1 of the drawings. The members 3 and 45 5 are preferably provided with the split lugs 6 through which screws or other fastening members 7 may be passed in order to firmly clamp the pipes 2 and 4 in position. Said members 3 and 5 are further 50 preferably provided with the flanges 8 adapted to rest firmly on the floor or other support 1, and said members 3 and 5 are still further provided with the enlarged lugs or solid members 9, each screw threaded as at 55 10 to receive the connecting heating pipe or member 11. The said solid members 9 are

further provided with the overhanging circumferential lips 12 adapted to receive the outer pipe 13 as shown.

Preferably integral with the said heating 60 members 3 and 5 are the end extensions 14 and 15 respectively, hollowed out as shown, and one of the same such as 15 provided with an orifice 16 which is screw threaded, and into which fits the valve plug 17, containing a spring controlled valve 18, all as will be clear from the drawings.

The member 3 and its associated parts 9 and 14 may be conveniently cast in a single piece and the same is true of the member 5. 70 I preferably further place a valve such as 20 in one of the members such as 3, and I conveniently attach to the valve stem 21 a handle 22 which plays over an arc 23 and thus indicates the degree to which the valve 75 20 has been closed. Any suitable liquid 26 may be introduced through the orifice 16 by removing the plug 17, and in case water is employed it is preferably desired to add alcohol, glycerin or some other compound to 80 prevent the same from freezing under ordinary temperature conditions.

In the form of the invention illustrated in Figs. 1 and 2, the foot rest projects above the floor 1 but it is entirely feasible to sink 85 the said rest below the said floor 1 as illustrated in Fig. 3 and to support it upon an extra piece such as 30, all as will be clear from the drawings.

It will thus be seen that I may employ 90 waste gases from the engine which may be conducted into and out of the heating pipe such as 11, and the heat of said gases is absorbed by a liquid such as water which is enabled to retain the heat long after the 95 gases have ceased to pass. That is to say, it is an important feature of this invention that a body of liquid such as 26 having a high specific heat is employed to absorb the waste heat from the engine so that the foot 100 warmer does not cool down suddenly when the engine stops as would be the case were no such liquid employed.

It is clear that both the arrangement of 105 parts as well as the details of construction may be varied, by those skilled in the art, without departing from the spirit of the invention, it is therefore desired not to be limited to the above disclosure except as may be required by the claims.

What is claimed is:—

1. In a combined foot rest and warmer

- the combination of a pair of end members each comprising a screw threaded lug member, each of said lug members having a circumferentially disposed overhanging lip 5 and a passage disposed at substantially right angles to its screw threaded portion; a pipe member rigid with each of said lug members and forming on their interiors continuations of said passages; hot gas induction 10 and eduction pipes joined to said pipe members; a centrally disposed pipe screw threaded at each end into one of said lug members and forming on its interior a continuation of said first named pipe members; 15 and an outer inclosing pipe fitting said circumferentially disposed overhanging lips, substantially as described.
2. In a combined foot rest and warmer the combination of a pair of hollow end 20 members provided with lugs having bores constituting passages for hot gases; a central pipe connecting said lugs and bores; an outer pipe adapted to form a foot rest
- also connecting said lugs; a pair of supporting pipe members communicating with 25 said bores and central pipe adapted to hold said end members and outer pipe above the floor of an automobile; and suitable connections between one of said supporting pipes and the exhaust of the engine, sub- 30 substantially as described.
3. In a combined foot rest and warmer the combination of a pair of hollow end members provided with lugs having overhanging lips and central bores for hot gases; a 35 central pipe fitting said bores; an outer pipe fitting said lips and adapted to form a foot rest; supporting pipes having bores connecting with said first named bores and having means to hold said end members and outer pipe above the floor of an automobile; and means to pass hot gases through said supporting pipes and said central pipe, sub- 40 substantially as described.

In testimony whereof I affix my signature. 45
FELIX H. PETITMAIRE.
